UNITED STATES PATENT OFFICE.

NORMAN H. SOOY, OF KANSAS CITY, MISSOURI.

PUMP-ROD-HANGER MECHANISM.

Application filed October 18, 1926. Serial No. 142,475.

My invention relates to improvements in pump rod hanger mechanism. It relates particularly to mechanisms for supporting on a walking beam a pump rod supporting 5 rope.

One of the objects of my invention is to provide a novel hanger mechanism of the kind described, which is simple, cheap, durable, strong, not liable to get out of order, 10 which can be readily applied to pumping mechanisms in common use, and which will reduce to a minimum the wear upon the rope and the bending of the pump rod.

A further object of my invention is to 15 provide a novel yoke adapted to be seated on a walking beam and to support the rope in a manner such that the latter will not be subject to kinking and undue wear when the beam is oscillated.

20 My invention provides still further novel means for adjusting the rope guiding mechanism to different operative positions on the walking beam.

The novel features of my invention are 25 hereinafter fully described and claimed.

In the accompanying drawings, which illustrate the preferred embodiment of my invention,

Fig. 1 is a side elevation of my improved 30 hanger mechanism shown mounted on a portion of a walking beam.

Fig. 2 is an end elevation of the same.

Fig. 3 is a top view of the same.

Fig. 4 is an enlarged section on the line 35 4—4 of Fig. 1.

Fig. 5 is a section on the line 5—5 of Fig. 4.

Fig. 6 is a section on the line 6—6 of Fig. 4.

40 Fig. 7 is an enlarged longitudinal section of one of the bearings for the braces on the walking beam and parts connected therewith.

Fig. 8 is a side elevation of what is shown 45 in Fig. 7.

Fig. 9 is a perspective view, reduced, of the mechanism shown in Fig. 1.

Similar reference characters designate 50 similar parts in the different views.

Fig. 1 designates a walking beam, such as is commonly used in oil or gas well pumping structures, pivoted on a horizontal shaft 2 mounted on a pedestal 3, a part of which is shown.

Fig. 4 designates the usual pumping or polish rod to which are attached, in any usual man-

ner, as by a clamping device 5, the end portions of a rope or wire cable 6.

For supporting the rope 6, I provide a yoke 7, the under side of which has a cylindrical bearing portion 8 which is pivotally mounted in a transverse groove 9 in the upper side of the walking beam 1, said groove being parallel with the axis or shaft 3 of the beam.

The upper side of the yoke 7 is provided with an inverted U-shaped arcuate groove 10, which serves as a seat in which the rope 6 is mounted. When the beam 1 is oscillated on the shaft 3, the yoke 7 will oscillate with 65 the rope 6, so that the latter will not kink or be sharply bent.

The yoke 7 is adapted to be used in connection with two arcuate guiding members 11 having guiding channels 12 for receiving 70 and guiding the rope 6. The members 11 are pivoted at their upper end portions, independently of the pivoting of the yoke 7, on a transverse bolt 13 disposed in the beam 1 so that the rope 6 will pass tangentially 75 to the yoke, the latter swinging to accommodate the position of the rope and to have its seat 10 aline with the channels 12.

To adjust and hold the guiding members 11 in different operative positions, with relation to the axis of the walking beam 1, so as to obtain a proper tangential relationship of the rope 6 with relation to the guiding members, and by which the lower ends of the members 11 may be adjusted toward and 80 from the axis of the beam 1, there are provided two bars 14, which are respectively pivoted to the members 11 adjacent to the lower ends thereof, and which respectively are longitudinally adjustable in two channel 85 plates 15, secured respectively to opposite sides of the beam 1.

Each bar 14 is threaded and has mounted on it at opposite ends of the adjacent channel plate 15, two nuts 16 which bear against 100 washers 17 on the bar and which bear against the ends of the plate 15. By adjusting the nuts 16, the bars 14 can be made to adjust the lower ends of the guiding members 11 to different operative positions and to different distances from the axis of the beam 1.

When used with the guiding members 11, the yoke 7 will swing on the beam 1 to properly guide the rope 6.

I do not limit my invention to the structure shown and described, as many modifications, within the scope of the appended

claims, may be made without departing from the spirit of my invention.

What I claim is:—

1. In a pump rod hanger mechanism, a walking beam having in its upper side parallel with its axis a transverse groove, a yoke pivotally mounted in said groove and free to oscillate on its axis when the beam oscillates and having in its upper side an arcuate seat adapted to have mounted in it a pump rod supporting rope, an arcuate guiding member pivoted independently of said yoke to said beam so as to align with said seat and adapted to engage and guide said rope, and bracing means connecting said beam and guiding member by which the latter may be adjusted to different operative positions.
2. In a pump rod hanger mechanism, a walking beam, an arcuate guiding member pivoted at its upper portion to said walking beam on an axis parallel with the axis of the beam and adapted to engage and guide a pump rod supporting rope, and means connecting said guiding member and said beam by which the lower end of said member may be adjusted to operative positions at different distances from the axis of said beam.
3. In a pump rod hanger mechanism, a walking beam, an arcuate guiding member pivoted at its upper portion to said beam

on an axis parallel with the axis of the walking beam, bearing means carried by said beam, and a longitudinally adjustable bracing bar pivoted to said guiding member and having a bearing against said bearing means, and arranged so that when adjusted the guiding member can be adjusted to operative positions, with the lower end of the guiding member at different distances from the axis 40 of said beam.

4. In a pump rod hanger mechanism, a walking beam, a yoke pivoted thereon on an axis parallel with the axis of the beam, the yoke having in its upper side an arcuate seat adapted to have mounted therein a pump rod supporting rope, the yoke being free to oscillate when the beam oscillates, and arcuate guiding means adapted to engage and guide said rope and pivotally adjustable on said beam on an axis parallel with the axis of the beam and independently of said yoke to operative positions at different distances from said axis of said beam, said yoke being disposed so as to swing to positions in which said rope will be held thereby tangent to said guiding means in the different positions of the latter.

In testimony whereof I have signed my name to this specification.

NORMAN H. SOOY.
